SPLIT RIM

Wade J. Webb, Oklahoma City, Okla.

Application April 1, 1939, Serial No. 265,418

1 Claim. (Cl. 301—63)

This invention relates to split rims for vehicles, and provides for maintaining each section of the rim structure in axial alignment with each other, and for protecting the assembly bolts from radial strains and shearing.

It is the purpose also of the invention to so distribute the bolt holes about one of the rim-sections as to equalize the strains upon the studs and the bolts when the parts are assembled.

10 On the sheet of drawings, accompanying and forming a part of the specification,

Figure 1 is a fragmented view in section and in elevation showing the assembly—the axle arrangement being obviously omitted;

15 Figure 2 is a similar view with nuts and bolts removed, showing the parts separated to show the seat features of the invention, and

Figure 3 is a frontal view, substantially diagrammatic and partially broken away, and which 20 shows the bolt hole disposition.

One section of the rim constitutes a formation including a casing bead 4, a casing wall 5, a casing seat 6, a tube well wall 7 and a well seat 8.

25 To the inner side of this seat 8 is welded a collar 9 from which extends in an inwardly direction two flanges 10 and 11, respectively, the latter being offset with relation to the former, and inwardly of the rim section by a seat 12.

30 Each flange 10 and 11 is provided with equidistantly disposed bolt holes 13 and 14, and these, in their respective equidistant arrangement are also relatively staggered for the purpose of equalizing the strain radially administered to the 35 bolt-body passing into the holes.

The rim section thus described is applied to studs 15 protruding from the face of a drum 16 and which pass through the openings 14 of the flange 11 and this flange is held to the drum face by the nuts 17.

40 An additional rim section is of formation providing a casing bead 18 from which laterally extends a casing seat 19 and a well wall 20, and this wall extends inwardly and is formed into a flange 21 shaped for complementary registry with the formation of flange 10 and is provided with bolt holes 13 for the bolts 22 which pass through the flange 10, and by which, together with the nuts 23 the second section of the rim is held to the first section.

45 The flange 21 terminates in a lip 24 which underrides the under face of the seat 12 on the companion rim, and is held tightly in place thereto by the bolts 22 and nuts 23.

This arrangement provides several important features, among the important of which is the axially aligned sections of the split rim, which insures an alignment of the casing seats 6 and 19, and the well walls 7 and 20. This provides 5 for the proper tractive stabilization of the casing and tends to forbid tractive inaccuracies in the traction of the casing, and case-torsion as well.

It is also to be observed that the interposition 10 of the seat 12, and the lip 24, between the bolts 15 and 22, and their positive fitting contact absorbs all of the radial strain and centrifugal expansion and thus forbids the transmission of either to any of the bolt-bodies, and this will 15 prevent bolt-body wearing or shearing, and thus preserve the axial alignment and balance of the rim-sections.

By staggering the equidistantly disposed sets of bolt holes 13 and 14, for instance, as shown 20 in Figure 3, such radial strains as are produced during rotation of the rim, will be relatively equidistantly distributed, and thus provide, not only for the constant contact of the face of the seat 12, and the face of the lip 24, but will insure the 25 aforesaid alignment; the uni-axial position of the rim-sections, and the face alignment of the casing seats 6 and 19, as well as the well walls 7 and 20.

This will centralize the tread of the casing, 30 and forbid torsion in the casing walls, and this will produce the much desired tractive efficiency so much sought.

The flange 21 is provided with an offset 25, which furnishes a seat 26 for the reception of 35 the edge of a hub-cap 27, which may be held in place by the usual clips 28.

Having thus set forth the invention, I claim:

A disc wheel comprising two wheel sections to be secured together to form a rim well, a vehicle drum for supporting the same, means to secure said sections together, and means to secure them to said drum, one wheel section including a rim well base, a flange integral therewith and having two axially offset portions each with a set of 40 bolt holes, a centering wall formed intermediate of said bolt holes, a second wheel section applicable to the first section and including a second flange for engaging part of said first flange, and a centering lip extending at right 45 angles from said second flange in the direction of the first section and telescoping within said centering wall.

WADE J. WEBB.
